LUMINAIRE

Myron F. Pettengill, Hendersonville, N.C., assignor to
General Electric Company, a corporation of New York

Filed Nov. 30, 1961, Ser. No. 67,749

Term of patent 14 years

(Cl. D48—31)

Fig. 3

Fig. 1

Fig. 2

Fig. 4

Fig. 5

FIG. 7.

FIG. 8.

FIG. 6.

FIG. 9.

FIG. 1 is a side elevational view of a luminaire showing my new design;

FIG. 2 is a bottom plan view; and

FIG. 3 is a top plan view thereof.

FIG. 4 is a side elevational view of a modified form of the luminaire of FIG. 1 having a top plan view as shown in FIG. 3; and

FIG. 5 is a bottom plan view thereof.

FIG. 6 is a side elevational view of a modified form of the luminaire of FIG. 1 having a bottom plan view as shown in FIG. 2; and

FIG. 7 is a top plan view thereof.

FIG. 8 is a side elevational view of a modified form of the luminaire of FIG. 1 having a top plan view as shown in FIG. 3; and

FIG. 9 is a bottom plan view thereof.

This application is a continuation in part of applications Serial Nos. D. 63,945 and D. 63,946, filed February 15, 1961, and now abandoned.

I claim:

The ornamental design for a luminaire, as shown and described.
